(57) **ABSTRACT**

An apparatus for processing soundfield data is provided. The soundfield data defines a soundfield within a spatial reproduction region comprising at least one bright zone and at least one quiet zone. The apparatus comprises an applicator configured to apply a spatially continuously varying weighting function to the soundfield data in order to obtain weighted soundfield data defining a weighted soundfield, wherein the spatially continuously varying weighting function is configured to enhance the soundfield in at least one of the bright zone and the quiet zone.

APPARATUS AND METHOD FOR
PROCESSING SOUNDFIELD DATACROSS-REFERENCE TO RELATED
APPLICATIONS

This application is a continuation of International Application No. PCT/EP2016/051677, filed on Jan. 27, 2016, the disclosure of which is hereby incorporated by reference in its entirety.

TECHNICAL FIELD

Generally, the present disclosure relates to the field of audio signal processing and reproduction. More specifically, the present disclosure relates to an apparatus and a method for processing and reproducing soundfield data.

BACKGROUND

Spatial multizone soundfield reproduction over an extended region of space has recently drawn increased attention due to its various applications such as simultaneous car entertainment systems, surround sound systems in exhibition centers, personal loudspeaker systems in shared office space, and quiet zones in a noisy environment, where the aim is to provide listeners an individual sound environment without having to use acoustical barriers or headphones. Generally, a soundfield can be considered to describe the deviations of the local air pressure from the ambient pressure, i.e. the pressure variations, as a function of space and time caused for instance by the sound signals emitted by a plurality of loudspeakers. A multizone soundfield usually can comprise one or more acoustically bright zones and possibly several acoustically quiet zones.

A so-called “non-robustness” problem of multizone sound reproduction was identified in Poletti, M., “An investigation of 2D multizone surround sound system,” Proc. AES 125th Convention Audio Eng. Society, 2008 in the form of a very obvious redundant sound between two selected regions with an amplitude even greater than the sound in the acoustically bright zone. In practice, such a behavior in a multizone soundfield can lead to unpleasant user experiences within these areas.

Thus, there is a need for improved apparatuses and methods for processing soundfield data addressing, in particular, the “non-robustness” problem described above.

SUMMARY

It is an object of the disclosure to provide an improved apparatus for processing soundfield data addressing, in particular, the “non-robustness” problem inherent to known devices and methods.

The foregoing and other objects may be achieved by the subject matter of the independent claims. Further implementation forms are apparent from the dependent claims, the description and the figures.

According to a first aspect the disclosure relates to an apparatus for processing soundfield data, wherein the soundfield data defines a soundfield within a spatial reproduction region comprising at least one acoustically bright zone and at least one acoustically quiet zone. The apparatus comprises: an applicator configured to apply a spatially continuously varying weighting function to the soundfield data in order to obtain weighted soundfield data defining a weighted soundfield, wherein the spatially continuously varying

2

weighting function is configured to enhance the soundfield in the bright zone and/or the quiet zone.

Applying a spatially continuously, i.e. smoothly, varying weighting function to the soundfield data defining a soundfield allows solving the “non-robustness problem” hampering known devices, by enhancing the soundfield in the bright zone and/or the quiet zone.

The term “soundfield data” is used herein to refer to any data which includes information relating to directional characteristics of the sound it represents. Soundfield data can be represented in a variety of different formats, each of which has a defined number of audio channels, and requires a different interpretation in order to reproduce the sound represented. Examples of such formats include stereo, 5.1 surround sound and formats such as Higher Order Ambisonic (HOA) formats, which use a spherical harmonic representation of the soundfield.

The spatial reproduction region of the soundfield defined by the soundfield data can have a plurality of different shapes. In an implementation form the soundfield can be three-dimensional or two-dimensional with the spatial reproduction region, the bright zone and the quiet zone lying in a two-dimensional plane. In an implementation form the bright zone and the quiet zone can have spherical, cylindrical or circular shapes. Other shapes are possible.

In a first possible implementation form of the apparatus according to the first aspect as such, the apparatus further comprises a compressor configured to compress the soundfield data on the basis of a performance measure associated with the weighted soundfield.

This allows adapting the compression rate applied by the compressor to the performance measure and, thus, reducing the size of the weighted soundfield data. This is advantageous, in particular, for implementation forms, where a compression, for instance, for transmission or storing, of the weighted soundfield data is separated in time and/or space from a decompression of the compressed weighted soundfield data, for instance, for reproducing the weighted soundfield data.

In a second possible implementation form of the apparatus according to the first implementation form of the first aspect, the compressor is configured to compress the soundfield data, in case the performance measure associated with the weighted soundfield differs from a predefined performance measure threshold.

By using predefined a performance measure threshold based, for instance, on measurements using live listeners, the compressor can efficiently decide when to adjust its compression rate.

In a third possible implementation form of the apparatus according to the first or the second implementation form of the first aspect, the performance measure associated with the weighted soundfield is an acoustical contrast between the at least one bright zone and the at least one quiet zone of the weighted soundfield.

In a fourth possible implementation form of the apparatus according to the third implementation form of the first aspect, the acoustical contrast between the bright zone and the quiet zone of the weighted soundfield is based on a ratio between an average of the weighted soundfield in the bright zone and an average of the weighted soundfield in the quiet zone.

In a fifth possible implementation form of the apparatus according to the fourth implementation form of the first aspect, the acoustical contrast between the bright zone and the quiet zone of the weighted soundfield is based on the following equation:

$$\epsilon(t) = 10\log_{10} \frac{\int_b |S(x, t)w(x)|^2 dx / D_b}{\int_q |S(x, t)w(x)|^2 dx / D_q},$$

wherein $\epsilon(t)$ denotes the acoustical contrast as a function of time, $S(x, t)$ denotes the soundfield data defining the soundfield as a function of space and time, $w(x)$ denotes the spatially continuously varying weighting function and D_b and D_q denote the size of the bright region and the size of the quiet region, respectively.

In a sixth possible implementation form of the apparatus according to the first aspect as such or any one of the first to fifth implementation form thereof, the spatially continuously varying weighting function is a smoothly changing function configured to enhance the soundfield associated with the soundfield data in the bright region and the quiet region relative to the portions of the spatial reproduction region outside of the bright region and the quiet region.

In a seventh possible implementation form of the apparatus according to the first aspect as such or any one of the first to sixth implementation form thereof, the spatially continuously varying weighting function is a linear combination of a first normal distribution centered at a center of the bright zone and a second normal distribution centered at a center of the quiet zone.

A normal distribution provides a good approximation for the random movements of the head of a listener relative to the center of the bright zone and the quiet zone, respectively.

In an implementation form the spatially continuously varying weighting function can be defined by the following equation:

$$w(x) = \frac{a}{\sigma_a \sqrt{2\pi}} e^{-\frac{(|x-O_b|)^2}{2\sigma_a^2}} + \frac{b}{\sigma_b \sqrt{2\pi}} e^{-\frac{(|x-O_q|)^2}{2\sigma_b^2}},$$

wherein $w(x)$ denotes the spatially continuously varying weighting function, O_b denotes the center of the bright zone, O_q denotes the center of the quiet zone and a , b , σ_a and σ_b denote predefined weighting function parameters.

In an eighth possible implementation form of the apparatus according to the first aspect as such or any one of the first to seventh implementation form thereof, the soundfield data is encoded in the HOA B-Format.

In a ninth possible implementation form of the apparatus according to the first aspect as such or any one of the first to eighth implementation form thereof, the apparatus further comprises a memory configured to store the soundfield data to be weighted by the spatially continuously varying weighting function. This can be done on the side of the encoder or on the side of the decoder.

In a tenth possible implementation form of the apparatus according to the first aspect as such or any one of the first to ninth implementation form thereof, the apparatus further comprises a renderer, in particular at least one loudspeaker, configured to render the weighted soundfield on the basis of the weighted soundfield data.

According to a second aspect the disclosure relates to a soundfield reproduction system comprising an apparatus for processing soundfield data according to the first aspect as such or any one of the first to tenth implementation form thereof and a soundfield reproduction apparatus, wherein the soundfield reproduction apparatus is configured to receive

the weighted soundfield data from the apparatus according to the first aspect and comprises a renderer, in particular at least one loudspeaker, configured to render the weighted soundfield on the basis of the weighted soundfield data.

5 In a first possible implementation form of soundfield reproduction system according to the second aspect as such, the soundfield reproduction apparatus further comprises a performance measure determiner configured to determine a performance measure on the basis of the weighted soundfield and to feedback the determined performance measure associated with the weighted soundfield to the compressor of the apparatus according to the first aspect.

According to a third aspect the disclosure relates to a method for processing soundfield data, wherein the soundfield data defines a soundfield within a spatial reproduction region comprising at least one bright zone and at least one quiet zone. The method comprises the step of applying a spatially continuously varying weighting function to the soundfield data in order to obtain weighted soundfield data defining a weighted soundfield, wherein the spatially continuously varying weighting function is configured to enhance the soundfield in the bright zone and/or the quiet zone.

15 In a first possible implementation form of the method according to the third aspect, the method comprises the further step of compressing the soundfield data on the basis of a performance measure associated with the weighted soundfield.

20 In a second possible implementation form of the method according to the first implementation form of the second aspect, the soundfield data is compressed, in case the performance measure associated with the weighted soundfield differs from a predefined performance measure threshold.

25 In a third possible implementation form of the method according to the first or the second implementation form of the second aspect, the performance measure associated with the weighted soundfield is an acoustical contrast between the at least one bright zone and the at least one quiet zone of the weighted soundfield.

30 In a fourth possible implementation form of the method according to the third implementation form of the second aspect, the acoustical contrast between the bright zone and the quiet zone of the weighted soundfield is based on a ratio between an average of the weighted soundfield in the bright zone and an average of the weighted soundfield in the quiet zone.

35 In a fifth possible implementation form of the method according to the fourth implementation form of the second aspect, the acoustical contrast between the bright zone and the quiet zone of the weighted soundfield is based on the following equation:

$$\epsilon(t) = 10\log_{10} \frac{\int_b |S(x, t)w(x)|^2 dx / D_b}{\int_q |S(x, t)w(x)|^2 dx / D_q},$$

55 wherein $\epsilon(t)$ denotes the acoustical contrast as a function of time $S(x, t)$ denotes the soundfield data defining the soundfield as a function of space and time, $w(x)$ denotes the spatially continuously varying weighting function and D_b and D_q denote the size of the bright region and the size of the quiet region, respectively.

60 In a sixth possible implementation form of the method according to the second aspect as such or any one of the first to fifth implementation form thereof, the spatially continu-

ously varying weighting function is a smoothly changing function configured to enhance the soundfield associated with the soundfield data in the bright region and the quiet region relative to the portions of the spatial reproduction region outside of the bright region and the quiet region.

In a seventh possible implementation form of the method according to the second aspect as such or any one of the first to sixth implementation form thereof, the spatially continuously varying weighting function is a linear combination of a first normal distribution centered at a center of the bright zone and a second normal distribution centered at a center of the quiet zone.

In an implementation form the spatially continuously varying weighting function can be defined by the following equation:

$$w(x) = \frac{a}{\sigma_a \sqrt{2\pi}} e^{-\frac{((x-O_b))^2}{2\sigma_a^2}} + \frac{b}{\sigma_b \sqrt{2\pi}} e^{-\frac{((x-O_q))^2}{2\sigma_b^2}},$$

wherein $w(x)$ denotes the spatially continuously varying weighting function, O_b denotes the center of the bright zone, O_q denotes the center of the quiet zone and a , b , σ_a and σ_b denote predefined weighting function parameters.

In an eighth possible implementation form of the method according to the second aspect as such or any one of the first to seventh implementation form thereof, the soundfield data is encoded in the HOA B-Format.

In a ninth possible implementation form of the method according to the second aspect as such or any one of the first to eighth implementation form thereof, the method comprises the further step of storing the soundfield data to be weighted by the spatially continuously varying weighting function in a memory.

In a tenth possible implementation form of the method according to the second aspect as such or any one of the first to ninth implementation form thereof, the method comprises the further step of rendering the weighted soundfield on the basis of the weighted soundfield data.

According to a fourth aspect the disclosure relates to a computer program comprising program code for performing the method according to the third aspect of the disclosure or any of its implementation forms when executed on a computer.

The disclosure can be implemented in hardware and/or software.

BRIEF DESCRIPTION OF THE DRAWINGS

Further embodiments of the disclosure will be described with respect to the following figures, wherein:

FIG. 1 shows a schematic diagram of an apparatus for processing soundfield data according to an embodiment;

FIG. 2 shows a schematic diagram of a method for processing soundfield data according to an embodiment;

FIG. 3 shows a schematic diagram of a soundfield reproduction system according to an embodiment comprising an apparatus for processing soundfield data according to an embodiment;

FIG. 4 shows a diagram illustrating the dependence of the averaged acoustic contrast performance as a function of a transmission bitrate for a plurality of different compression techniques that can be implemented in a soundfield reproduction system shown in FIG. 3;

FIG. 5 shows a schematic diagram of an apparatus for processing soundfield data according to an embodiment;

FIG. 6 shows a schematic diagram illustrating different aspects of embodiments of the disclosure; and

FIG. 7 shows a schematic diagram illustrating different aspects of embodiments of the disclosure.

In the various figures, identical reference signs will be used for identical or at least functionally equivalent features.

DETAILED DESCRIPTION OF THE EMBODIMENTS

In the following description, reference is made to the accompanying drawings, which form part of the disclosure, and in which are shown, by way of illustration, specific aspects in which the present disclosure may be placed. It is understood that other aspects may be utilized and structural or logical changes may be made without departing from the scope of the present disclosure. The following detailed description, therefore, is not to be taken in a limiting sense, as the scope of the present disclosure is defined by the appended claims.

For instance, it is understood that a disclosure in connection with a described method may also hold true for a corresponding device or system configured to perform the method and vice versa. For example, if a specific method step is described, a corresponding device may include a unit to perform the described method step, even if such unit is not explicitly described or illustrated in the figures. Further, it is understood that the features of the various exemplary aspects described herein may be combined with each other, unless specifically noted otherwise.

FIG. 1 shows a schematic diagram of an apparatus 100 for processing soundfield data. As schematically indicated on the right hand side of FIG. 1, the soundfield data defines a soundfield within a spatial reproduction region 101 comprising at least one bright zone 101a and at least one quiet zone 101b.

The term "soundfield data" is used herein to refer to any data which includes information relating to directional characteristics of the sound it represents. Soundfield data can be represented in a variety of different formats, each of which has a defined number of audio channels, and requires a different interpretation in order to reproduce the sound represented. Examples of such formats include stereo, 5.1 surround sound and formats such as Higher Order Ambisonic (HOA) formats, in particular HOA B-format.

The spatial reproduction region of the soundfield defined by the soundfield data can have a plurality of different shapes. In an implementation form the soundfield can be three-dimensional or two-dimensional with the spatial reproduction region, the bright zone and the quiet zone lying in a two-dimensional plane. In an implementation form the bright zone and the quiet zone can have spherical, cylindrical or circular shapes. Other shapes are possible.

The apparatus 100 comprises an applicator 103 configured to apply a spatially continuously varying weighting function to the soundfield data in order to obtain weighted soundfield data defining a weighted soundfield. The spatially continuously varying weighting function is configured to enhance the soundfield in the bright zone 101a and/or the quiet zone 101b of the spatial reproduction region 101.

In an embodiment, the apparatus 100 further comprises a compressor 105 configured to compress the soundfield data on the basis of a performance measure associated with the weighted soundfield.

In an embodiment, the compressor 105 is configured to compress the soundfield data, in case the performance measure associated with the weighted soundfield differs from a predefined performance measure threshold.

In an embodiment, the performance measure associated with the weighted soundfield is an acoustical contrast between the at least one bright zone 101a and the at least one quiet zone 101b of the weighted soundfield.

In an embodiment, the acoustical contrast between the bright zone 101a and the quiet zone 101b is based on a ratio between an average of the weighted soundfield in the bright zone 101a and an average of the weighted soundfield in the quiet zone 101b.

In an embodiment, the acoustical contrast between the bright zone 101a and the quiet zone 101b is based on the following equation:

$$\epsilon(t) = 10\log_{10} \frac{\int_b |S(x, t)w(x)|^2 dx / D_b}{\int_q |S(x, t)w(x)|^2 dx / D_q}, \quad (1)$$

wherein $\epsilon(t)$ denotes the acoustical contrast as a function of time, $S(x, t)$ denotes the soundfield associated with the soundfield data as a function of space and time, $w(x)$ denotes the spatially continuously varying weighting function and D_b and D_q denote the size of the bright region 101a and the size of the quiet region 101b, respectively.

In an embodiment, the spatially continuously varying weighting function is a smoothly changing function configured to enhance the soundfield associated with the soundfield data in the bright region 101a and the quiet region 101b relative to the portions of the spatial reproduction region 101 outside of the bright region 101a and the quiet region 101b.

In an embodiment, the spatially continuously varying weighting function is a linear combination of a first normal distribution centered at a center of the bright zone 101a and a second normal distribution centered at a center of the quiet zone 101b. This preferred choice of the spatially continuously varying weighting function is based on the finding that, in practice, the position of the listener's head (ears) is not guaranteed to be stationary within the bright region and/or quiet region due to the movement of its body. Rather, the distribution of listener's head position can be modelled as a Gaussian distribution function of its distance to the center of the bright zone and the quiet zone, respectively. Thus, in an embodiment, the spatially continuously varying weighting function can be defined by the following equation:

$$w(x) = \frac{a}{\sigma_a \sqrt{2\pi}} e^{-\frac{||x-O_b||^2}{2\sigma_a^2}} + \frac{b}{\sigma_b \sqrt{2\pi}} e^{-\frac{||x-O_q||^2}{2\sigma_b^2}}, \quad (2)$$

wherein $w(x)$ denotes the spatially continuously varying weighting function, O_b denotes the center of the bright zone, O_q denotes the center of the quiet zone and a , b , σ_a and σ_b denote predefined weighting function parameters.

With the above preferred choice for the weighting function the probability that the listener's head is positioned within a circle of radius $r/2$ from the center of the bright zone (or equivalently the center of the quiet zone) is 68.3%. With this choice of the weighting function, the system will distribute the importance of the reproduction accuracy over

different zones in a more flexible and efficient manner due to the introduction of the smoothly and continuously changing weighting function. More emphasis will be attached to the region where the listener's ears are more likely to appear (e.g. the central region of the bright and quiet zone), while the reproduction effort might be distracted in some region (e.g. the edge of the bright and quiet zone) in order to alleviate the occurrence of spurious sound outside of the bright zone and the quiet zone.

FIG. 2 shows a schematic diagram of a method 200 for processing soundfield data according to an embodiment, for instance, the soundfield data defining a soundfield within the spatial reproduction region 101 shown in FIG. 1, comprising the acoustically bright zone 101a and the acoustically quiet zone 101b.

The method 200 comprises the step 201 of applying a spatially continuously varying weighting function to the soundfield data, for instance, the spatially continuously varying weighting function defined in equation (2) above, in order to obtain weighted soundfield data defining a weighted soundfield, wherein the spatially continuously varying weighting function is configured to enhance the soundfield in the bright zone 101a and/or the quiet zone 101b.

Further implementation forms, embodiments and aspects of the apparatus 100 for processing soundfield data and the method 200 for processing soundfield data will be described in the following.

FIG. 3 shows a schematic diagram of a soundfield reproduction system 300 according to an embodiment comprising an apparatus 100 for processing soundfield data according to an embodiment.

In the embodiment of the apparatus 100 for processing soundfield data shown in FIG. 3, the applicator 103 shown in FIG. 1 is referred to as a "Multizone HOA format converter" 103 and the compressor 105 shown in FIG. 1 is referred to as "Compression". In addition to the applicator 103 and the compressor 105 the embodiment of the apparatus 100 for processing soundfield data shown in FIG. 3 comprises an acquisition device 107 configured to acquire the original, i.e. non-weighted, soundfield data. In an embodiment, the acquisition device 107 can comprise one or more microphones, such as a 32-channel Eigenmike. In an embodiment, the acquisition device 107 can be a communication interface configured to receive the original, i.e. non-weighted, soundfield data from another device.

In an embodiment, the acquisition device 107 is configured to provide the original, i.e. non-weighted, soundfield data in HOA B-format to a HOA format converter 109 configured to perform a plane wave decomposition of the HOA B-format soundfield data into the spherical/circular harmonic domain resulting in the soundfield data $S(x, k)$, wherein x denotes the position vector and k denotes the wave number, or equivalently the soundfield data $S(x, t)$, wherein t denotes time.

The HOA format converter 109 of the embodiment of the apparatus 100 for processing soundfield data shown in FIG. 3 is configured to provide the soundfield data $S(x, k)$ (or equivalently $S(x, t)$) to the applicator 103, which, as already mentioned above, in the embodiment shown in FIG. 8 is referred to as the "Multizone HOA format converter" 103. As already described in the context of the embodiment shown in FIG. 1, the applicator 103 is configured to apply a spatially continuously varying weighting function to the soundfield data provided by the HOA format converter 109 in order to obtain weighted soundfield data defining a weighted soundfield. The spatially continuously varying weighting function used by the applicator 103 is configured

to enhance the soundfield in the bright zone **101a** and/or the quiet zone **101b** of the spatial reproduction region **101**. In an embodiment, the applicator **103** is configured to provide the weighted soundfield data as HOA-B format weighted soundfield data. As schematically indicated in FIG. 3, in order to be able to perform this conversion to the HOA-B format, the applicator **103** requires as input some information about the soundfield and the weighting function, such as the location of the bright zone and/or the quiet zone.

In the embodiment shown in FIG. 3, the apparatus **100** for processing soundfield data comprises in addition an electronic storage or memory **111** configured to store soundfield data to be processed by the applicator **103**, i.e. to be weighted by the spatially continuously varying weighting function. Thus, in embodiments, the applicator **103** can be configured to process soundfield data provided by either one or by both of the HOA format converter **109** or the storage **111**.

In the embodiment shown in FIG. 3 the weighted soundfield data generated by the applicator **103** is provided to the compressor **105**, which is configured to compress the weighted soundfield data using one or more conventional compression techniques. As will be described in more detail further below, in an embodiment, the compressor **105** is configured to adapt its compression rate for compressing the weighted soundfield data on the basis of a performance measure, which is being fed back to the compressor **105** from the soundfield reproduction apparatus **310** shown in FIG. 3.

In the embodiment shown in FIG. 3 the apparatus **100** for processing soundfield data and the soundfield reproduction apparatus **310** are part of the soundfield reproduction system **300**. In other embodiment, the apparatus **100** for processing soundfield data and the soundfield reproduction apparatus **310** can be separated in space and/or time. For instance, the apparatus **100** for processing soundfield data could be implemented as a web server providing the compressed weighted soundfield data over the Internet to the soundfield reproduction apparatus **310** implemented as a web client. In such a scenario the apparatus **100** for processing soundfield data can be considered to be an encoder, whereas the soundfield reproduction apparatus **310** can be considered to be a corresponding decoder.

In the embodiment shown in FIG. 3, the soundfield reproduction apparatus **310** comprises a decompressor **312** configured to decompress the compressed weighted soundfield data provided by the apparatus **100** for processing soundfield data. In case the compressor **105** and the decompressor **312** are implemented to use lossless compression techniques the decompressor **312** can fully restore the weighted soundfield data. Furthermore, the soundfield reproduction apparatus **310** comprises a renderer **313** configured to render, i.e. reproduce the weighted soundfield on the basis of the weighted soundfield data. In an embodiment, the renderer **313** can comprise one or more appropriately arranged transducers, in particular loudspeakers.

Finally, in the embodiment shown in FIG. 3, the soundfield reproduction apparatus **310** comprises a performance measure determiner **315** configured to determine a performance measure on the basis of the weighted soundfield. To this end, in an embodiment, the performance measure determiner **315** can comprise one or more microphones, such as a 32-channel Eigenmike, for measuring the weighted soundfield reproduced by the renderer **313** as well as a processing unit configured to determine a performance measure on the basis of the measured weighted soundfield, for instance, the performance measure defined in equation (1) above.

In an embodiment, the soundfield reproduction apparatus **310** is configured to feedback the performance measure determined by the performance measure determiner **315** to the compressor **105** of the apparatus **100**. In an embodiment, the compressor **105** is configured to adjust its compression rate on the basis of the performance measure provided by the performance measure determiner **315**. For instance, in an embodiment the compressor **105** can check, whether the performance measure provided by the performance measure determiner **315** is larger than a predefined performance measure threshold, e.g. whether the acoustical contrast between the bright region **101a** and the quiet region is larger than a predefined minimal acoustical contrast, and, if this is the case, can increase the compression rate applied to the weighted soundfield data.

In an embodiment, the compressor **105** can implement a compression strategy based on the pre-calculated graphs shown in FIG. 4, which shows the dependence of the averaged acoustic contrast performance as a function of a transmission bitrate for a plurality of different compression techniques, such as different versions of EVS and different versions of AAC. For instance, in an embodiment, the compressor **105** could be configured to increase its compression rate, in case for a given previously chosen bitrate the performance measure provided by the performance measure determiner **315**, i.e. the averaged acoustic contrast performance, falls below the curve shown in FIG. 4 for the compression strategy adopted by the compressor **105**.

FIG. 5 shows a schematic diagram of a further embodiment of an apparatus **100** for processing soundfield data. As the embodiment of the apparatus **100** for processing soundfield data shown in FIG. 1, the further embodiment of the apparatus **100** for processing soundfield data shown in FIG. 5 comprises an applicator **103** (referred to as "Multizone HOA format converter" in FIG. 5) configured to apply a spatially continuously varying weighting function to soundfield data, for instance, the spatially continuously varying weighting function defined in equation (2) above, in order to obtain weighted soundfield data defining a weighted soundfield, wherein the spatially continuously varying weighting function is configured to enhance the soundfield in the bright zone **101a** and/or the quiet zone **101b**. In the embodiment shown in FIG. 5, the soundfield data is taken from an electronic storage or memory **111**, for instance a DVD player, a CD player or a Flash memory, configured to store the soundfield data to be weighted by the spatially continuously varying weighting function. In an embodiment, the applicator **103** is configured to provide the weighted soundfield data as HOA-B format weighted soundfield data. As schematically indicated in FIG. 5, in order to be able to perform this conversion to the HOA-B format, the applicator **103** requires as input some information about the soundfield and the weighting function, such as the location of the bright zone and/or the quiet zone.

As in the embodiment shown in FIG. 5, the weighted soundfield data is provided from the applicator **103** directly to a renderer **113** configured to render, i.e. reproduce, the weighted soundfield on the basis of the weighted soundfield data, the apparatus **100** shown in FIG. 5 does not comprise a compressor, such as the compressor **105** of the apparatus shown in FIG. 1.

FIGS. 6 and 7 show schematic diagrams illustrating different aspects of embodiments of the disclosure in the context of an unrestricting illustrative example. In this illustrative example it is assumed that the bright zone of the weighted soundfield has the size of a circle with diameter $2*Ro$ (outer zone) as shown in FIG. 6, which generally

11

is much larger than the size of an average human head. As already described above, according to embodiments of the disclosure, a bitrate reduction can be achieved by having a smooth weighting function/model corresponding to some criteria such as the possible user movement within the region of diameter 2^*R_i (inner zone) inside the outer zone.

In multizone applications, it is practically desirable to have the size of outer zone as large as possible. One may choose to focus on the reproduction inside a smaller region denoted by the inner zone. This will make the system to be inferior due to a smaller area of coverage and reprocessing of the multizone HOA B-format signals due to a change in the multizone arrangement input, resulting in an undesired quality as the user moves away from the inner zone. Embodiments of the disclosure on the other hand, guarantee a smooth transition in quality as highlighted in FIG. 7.

While a particular feature or aspect of the disclosure may have been disclosed with respect to only one of several implementations or embodiments, such feature or aspect may be combined with one or more other features or aspects of the other implementations or embodiments as may be desired and advantageous for any given or particular application. Furthermore, to the extent that the terms "include", "have", "with", or other variants thereof are used in either the detailed description or the claims, such terms are intended to be inclusive in a manner similar to the term "comprise". Also, the terms "exemplary", "for example" and "e.g." are merely meant as an example, rather than the best or optimal. The terms "coupled" and "connected", along with derivatives may have been used. It should be understood that these terms may have been used to indicate that two elements cooperate or interact with each other regardless whether they are in direct physical or electrical contact, or they are not in direct contact with each other.

Although specific aspects have been illustrated and described herein, it will be appreciated by those of ordinary skill in the art that a variety of alternate and/or equivalent implementations may be substituted for the specific aspects shown and described without departing from the scope of the present disclosure. This application is intended to cover any adaptations or variations of the specific aspects discussed herein.

Although the elements in the following claims are recited in a particular sequence with corresponding labeling, unless the claim recitations otherwise imply a particular sequence for implementing some or all of those elements, those elements are not necessarily intended to be limited to being implemented in that particular sequence.

Many alternatives, modifications, and variations will be apparent to those skilled in the art in light of the above teachings. Of course, those skilled in the art readily recognize that there are numerous applications of the disclosure beyond those described herein. While the present disclosure has been described with reference to one or more particular embodiments, those skilled in the art recognize that many changes may be made thereto without departing from the scope of the present disclosure. It is therefore to be understood that within the scope of the appended claims and their equivalents, the disclosure may be practiced otherwise than as specifically described herein.

What is claimed is:

1. An apparatus for processing soundfield data, the soundfield data defining a soundfield within a spatial reproduction region comprising an at least one bright zone and an at least one quiet zone, the apparatus comprising:

an applicator that applies a spatially continuously varying weighting function to the soundfield data to obtain a

12

weighted soundfield data defining a weighted soundfield, wherein the spatially continuously varying weighting function enhances the soundfield in at least one of the group consisting of: the at least one bright zone and the at least one quiet zone; and

a compressor that compresses the soundfield data based on a performance measure associated with the weighted soundfield.

2. The apparatus of claim 1, wherein the compressor compresses the soundfield data, in a case where the performance measure associated with the weighted soundfield differs from a predefined performance measure threshold.

3. The apparatus of claim 1, wherein the performance measure associated with the weighted soundfield is an acoustical contrast between the at least one bright zone and the at least one quiet zone of the weighted soundfield.

4. The apparatus of claim 3, wherein the acoustical contrast between the bright zone and the quiet zone is obtained based on a ratio between an average of the weighted soundfield in the at least one bright zone and an average of the weighted soundfield in the at least one quiet zone.

5. The apparatus of claim 3, wherein the acoustical contrast between the at least one bright zone and the at least one quiet zone is obtained based on the following:

$$\epsilon(t) = 10 \log_{10} \frac{\int_b |S(x, t)w(x)|^2 dx / D_b}{\int_q |S(x, t)w(x)|^2 dx / D_q},$$

wherein $\epsilon(t)$ denotes the acoustical contrast as a function of time (t), $S(x, t)$ denotes the soundfield data defining the soundfield as a function of a space and a time, $w(x)$ denotes the spatially continuously varying weighting function and D_b and D_q denote a size of the at least one bright zone and a size of the at least one quiet zone, respectively.

6. The apparatus of according to claim 1, wherein the spatially continuously varying weighting function is a smoothly changing function that enhances the soundfield associated with the soundfield data in the at least one bright zone and the at least one quiet zone relative to a portion of the spatial reproduction region outside of the at least one bright zone and the at least one quiet zone.

7. The apparatus according to claim 1, wherein the spatially continuously varying weighting function is a linear combination of a first normal distribution centered at a center of the at least one bright zone and a second normal distribution centered at a center of the at least one quiet zone.

8. The apparatus according to claim 1, wherein the soundfield data is encoded in a Higher Order Ambisonic (HOA) B-Format.

9. The apparatus according to claim 1, wherein the apparatus further comprises a memory that stores the soundfield data to be weighted by the spatially continuously varying weighting function.

10. The apparatus according to claim 1 further comprising a renderer that renders the weighted soundfield based on the weighted soundfield data.

11. The apparatus of claim 1 further comprising: a soundfield reproduction apparatus that receives the weighted soundfield data; and a renderer that renders the weighted soundfield based on the weighted soundfield data.

13

12. The apparatus of claim 11, wherein the soundfield reproduction apparatus further comprises a performance measure determiner that determines the performance measure based on the weighted soundfield and feeds back the performance measure associated with the weighted soundfield to the compressor.

13. A method for processing a soundfield data, the soundfield data defining a soundfield within a spatial reproduction region comprising an at least one bright zone and an at least one quiet zone, the method comprising:

10 applying a spatially continuously varying weighting function to the soundfield data to obtain a weighted soundfield data defining a weighted soundfield, wherein the spatially continuously varying weighting function enhances the soundfield in the at least one of the group consisting of: the at least one bright zone and the at least one quiet zone; and

15 compressing the soundfield data based on a performance measure associated with the weighted soundfield.

14. The method of claim 13, wherein the performance measure associated with the weighted soundfield is an acoustical contrast between the at least one bright zone and the at least one quiet zone of the weighted soundfield.

15. The method of claim 14, wherein the acoustical contrast between the bright zone and the quiet zone is obtained based on a ratio between an average of the weighted soundfield in the at least one bright zone and an average of the weighted soundfield in the at least one quiet zone.

16. The method of claim 14, wherein the acoustical contrast between the at least one bright zone and the at least one quiet zone is obtained based on the following:

$$\epsilon(t) = 10 \log_{10} \frac{\int_b |S(x, t)w(x)|^2 dx / D_b}{\int_q |S(x, t)w(x)|^2 dx / D_q},$$

40 wherein $\epsilon(t)$ denotes the acoustical contrast as a function of time (t), $S(x, t)$ denotes the soundfield data defining the soundfield as a function of a space and a time, $w(x)$ denotes the spatially continuously varying weighting function and D_b and D_q denote a size of the at least one bright zone and a size of the at least one quiet zone, respectively.

14

5 17. A non-transitory computer readable storage medium having a computer-executable instructions that, when executed by a processor, facilitate carrying out a method for processing a soundfield data, the soundfield data defining a soundfield within a spatial reproduction region comprising an at least one bright zone and an at least one quiet zone, the method comprising:

10 applying a spatially continuously varying weighting function to the soundfield data to obtain a weighted soundfield data defining a weighted soundfield, wherein the spatially continuously varying weighting function enhances the soundfield in the at least one of the group consisting of: the at least one bright zone and the at least one quiet zone; and

15 compressing the soundfield data based on a performance measure associated with the weighted soundfield.

18. The non-transitory computer-readable medium of claim 17, wherein the performance measure associated with the weighted soundfield is an acoustical contrast between the at least one bright zone and the at least one quiet zone of the weighted soundfield.

20 19. The non-transitory computer-readable medium of claim 18, wherein the acoustical contrast between the bright zone and the quiet zone is obtained based on a ratio between an average of the weighted soundfield in the at least one bright zone and an average of the weighted soundfield in the at least one quiet zone.

25 20. The non-transitory computer-readable medium of claim 18, wherein the acoustical contrast between the at least one bright zone and the at least one quiet zone is obtained based on the following:

$$35 \epsilon(t) = 10 \log_{10} \frac{\int_b |S(x, t)w(x)|^2 dx / D_b}{\int_q |S(x, t)w(x)|^2 dx / D_q},$$

40 wherein $\epsilon(t)$ denotes the acoustical contrast as a function of time (t), $S(x, t)$ denotes the soundfield data defining the soundfield as a function of a space and a time, $w(x)$ denotes the spatially continuously varying weighting function and D_b and D_q denote a size of the at least one bright zone and a size of the at least one quiet zone, respectively.
